(57) **CLAIM**

The ornamental design for a catheter hub as shown and described.

DESCRIPTION

2. Catheter hub

Fig. 2.1 is a front, right, and top perspective view of a catheter hub showing the new design; Fig. 2.2 is a front elevation view thereof;

Fig. 2.3 is a rear elevation view thereof;

Fig. 2.4 is a left side view thereof;

Fig. 2.5 is a right side view thereof;

Fig. 2.6 is a top view thereof;

Fig. 2.7 is a bottom view thereof;

Fig. 2.8 is a rear, left, and bottom perspective view thereof;

Fig. 2.9 is an enlarged view thereof, illustrating a portion of the catheter hub identified by reference numeral 2.9 in Fig. 2.1;

Fig. 2.10 is an enlarged view thereof, illustrating a portion of the catheter hub identified by reference numeral 2.10 in Fig. 2.8; and

Fig. 2.11 is an enlarged view of Fig. 2.5.

The broken (dashed) lines show portions of the catheter hub that form no part of the claimed design. The dot-dash lines

(Continued)

shown in the reproductions indicate the position of the enlarged views and form no part of the claimed design.
